CLAMP

Eli Sampson, Marshfield, Oreg.

Application November 24, 1939, Serial No. 305,908

1 Claim. (Cl. 144—299)

My invention relates to bar clamps, commonly used in wood-working shops, which may be extended to twice their unextended length.

At present, wood-working shops must have on hand not only a great number of clamps, but a great variety of lengths, to meet the varied demands of their customers. An object of my invention is to cut down the number of clamps usually required.

Clamps are also needed on the job and it becomes necessary for journeymen to carry clamps, sometimes very long ones, from the shop to the job, and from job to job. Long clamps are very inconvenient to carry about. Another object of my invention is to provide a clamp, that may be readily carried about in the average hand box, whose range of usefulness may be doubled.

The accompanying sheet of drawings discloses one design of my invention. Fig. 1, is a side view of the clamp partially extended; Fig. 2, is a top view of Fig. 1; Fig. 3, is an isometric view of the T-shaped head or dog on the intermediate or extension bar; Fig. 4, is a section on 4—4 of Fig. 1; Fig. 5, is a section on 5—5 of Fig. 1; Fig. 6, is an end view of the dog on the tail work-engaging fixture; and Fig. 7, is a partial end view of the clamp with the tail fixture dog removed.

Throughout the drawing and this specification similar numerals refer to similar parts.

In the design which I have used to illustrate my invention, the clamp A comprises two sections, the long side bar assembly B and the short side bar assembly C. Normally the bars of both sections are in longitudinal alignment, as shown by the solid lines in Fig. 1. When the length of the clamp is being altered, assembly C is first tilted as shown by its dot and dash outline 3 of Fig. 1, whereby the two assemblies are disengaged and assembly C may be shifted longitudinally with respect to assembly B to shorten or lengthen the clamp A.

The assembly B includes two long rectangular side bars 4 and 5 held together in spaced apart relation by an inverted T-shaped spreader 6 whose leg portion 7 is interposed between the head end of said bars and secured to them, in the instant case, by welding, the method which I have employed to fixedly join parts of my clamp. The head portion 8 of the spreader 6 depends beneath the side bars 4 and 5 with each of its shoulders 9 in intimate contact with the face 10 of the bar above, the outer face 11 of said head portion being flush with the outer face 12 of said bars. The head portion 8 serves as an abutment for the

head work-engaging fixture 13 which is provided with an aperture 14 for the reception of the side bars 4 and 5 upon which said fixture is a sliding fit. A portion 15 of the fixture 13 depends beneath the side bars and terminates in a widened work-engaging portion 16. The portion 15 is provided with a bearing aperture 17 for the reception of the turned down end 18 of the screw 19 which is threaded into and thru the head portion 8. The other end of said screw 19 extending outside and rearwardly of the head portion 8 terminates in a crank arm 20 disposed at right angles thereto. This crank arm 20 is provided with a handle 21 extending at right angles thereto whereby the movement of the screw 19 may be manually controlled by the clamp user in moving the fixture 13 longitudinally forward or back on the side bars 4 and 5. The end 18 of the screw 19 is provided with an annular groove 22 into which extends the turned down end 23 of the screw 24 threaded into the portion 15 of the fixture 13 whereby said fixture is caused to move in accordance with the screw movement.

The opposite end of the side bars 4 and 5 are held together in spaced apart relation by the top tie plate 25 secured in the dap 26 formed in the upper face 27 of and at the end of said bars. The lower tie plate 28 is secured in the dap 29 formed in the lower face 10 of the bars rearwardly of the upper dap. This arrangement provides upper and lower confining and supporting means for the short bar assembly C and permits said assembly to be tilted as shown and above described. By setting the tie plates in the daps the outer faces may be flush with the outer faces of the bars thereby eliminating obstructions to the free movement of fixtures over said bars.

The short side bar assembly C includes an elongated rectangular intermediate or extension bar 30 to the sides 31 of which, at one of its ends, is secured two short bars 4a and 5a similar in cross section to the long bars 4 and 5. The intermediate bar may have the same thickness as the side bars or it may be proportioned to provide the same strength as the both long side bars 4 and 5 combined. However, its width and thickness must be such as to permit it to be slidable thru and between the tie plates and side bars of assembly B.

A wedge-shaped T-head or dog 32 is fixedly secured at the opposite end of the intermediate bar 30 with the top face 33 of said head flush with the top face 27 of the side bars 4 and 5, and 4a and 5a, which have notches cut in their top

face 27 similar to and to receive said wedge-shaped T-head. The notch 34a is cut adjacent the head fixture 13 when the same abuts the head portion 8 of the spreader 6. The notch 34b is cut adjacent the top tie plate 25, while the notches 34 are equally spaced between the notches 34a and 34b. The short side bars 4a and 5a are provided with at least one notch 34c. This notch 34c is engageable only by the dog 35 on the tail work-engaging fixture 36, while the notches 34, 34a, and 34b, are only engageable by the T-shaped head or dog 32, whereby the intermediate bar 30 is held in any desired working relation to the side bars 4 and 5. When the end 37 of the short side bars abuts the end 38 of the long side bars, the proportion and arrangement of parts is such that the T-head or dog 32 is in engagement with the notch 34a. By tilting assembly C as shown in Fig. 1, the same may be moved longitudinally outward to engage any of the notches 34 or the notch 34b, in which latter instance the distance between the work-engaging fixture 13 and 36 is doubled. The tail working-engaging fixture 36 may be moved longitudinally over the side bars of either assembly and its dog 35 may engage any of the notches of the clamp. It is to be noted and remarked that the two assemblies are not separable when once the T-shaped head is fixed to the intermediate bar 30. The head must be secured to the bar after the same has been passed thru the tie plates and is between the side bars.

The tail work-engaging fixture 36 is provided with an aperture 39 for the reception of the side bars 4 and 5 or 4a and 5a upon which said fixture is a sliding fit. The fixture 36 has a portion 40 which depends below the side bars and which terminates in a widened work-engaging portion 41 whose work-engaging face 42 is adjacent to the work-engaging face 43 on head fixture 13. The fixture 36 also has a portion 44 which extends above the side bars and has its leading upper corner bifurcated to form a pair of ears 45 spaced apart for the reception of a dog 46 hinged on a pin 47 press fitted in said ears. In forming said ears thus, a wedge-shaped tie member 48 is left to ride upon the side bars and form a support for the fixture. The lower

portion 49 of the dog 46 is formed to fit and for engagement of any of the notches in the clamp, and is readily lifted out of said engagement by depressing the upper end 50. To prevent the accidental removal of the fixture 36 from assembly C, the stop pins 51 are provided in the side bars 4a and 5a. Since the notches are formed in the side bars, and the intermediate bar is positioned between them, the dog 46 is notched as shown in Fig. 6, to straddle said intermediate bar since it extends into the notches.

The basic idea of my invention has been incorporated in a design which has been minutely shown and described and which in practice works perfectly. However, the design admits of changes in form and arrangement without departing from the basic idea and therefor I do not limit my invention to the design shown and described but extend it to all that comes fairly within the scope of the appended claims.

I claim:

In a clamp, the combination of a pair of long rectangular side bars; a pair of similar short side bars; a plurality of notches formed in the upper face of the bars, at least one of which is in the short bars; means to hold the long side bars together in spaced apart relation including a top tie plate at one end of said bars and a bottom tie plate spaced rearwardly of the top tie plate; an intermediate rectangular bar having one of its ends secured between the short side bars and its opposite end provided with transverse ears which together with the bar end form a T-shaped head, said ears being shaped to engage a notch in the long side bars, said intermediate bar being slidable longitudinally between said tie plates and said long side bars and normally parallel to said side bars and tilted thereto when the head is being moved from one notch to another; a work-engaging head fixture slidable longitudinally on the long side bars; means to control its movement; a work-engaging tail fixture slidable longitudinally on both the long and short side bars and having a dog to engage a notch on either of said bars, the top and bottom edges of the bars between the head and tail fixtures being free of work-marring projections.

ELI SAMPSON.
